(57) CLAIM

An ornamental design of a dual-sole shoe with green outpatch sole and contrasting upper, as shown and described.

DESCRIPTION

The file of this patent contains at least one drawing executed in color. Copies of this patent with color drawing(s) will be provided by the Office upon request and payment of the necessary fee.

FIG. 1 is a perspective view of yet another embodiment of our new design of a dual-sole shoe with color outpatch sole and contrasting upper, where the portions of the upper and the midsole that contrast with the outpatch sole are indicated using a dotted pattern;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;

FIG. 7 is a back view of the design of FIG. 1;

FIG. 8 is a perspective view of yet another embodiment of our new design of a dual-sole shoe with color outpatch sole and contrasting upper, where the color portions are indicated using the USPTO convention of solid diagonal lines extending from the upper left to the lower right for green, and where the portions of the upper and the midsole that contrast with the outpatch sole are indicated using a dotted pattern;

FIG. 9 is a first side view of the design of FIG. 8;
FIG. 10 is a second side view of the design of FIG. 8;
FIG. 11 is a top view of the design of FIG. 8;
FIG. 12 is a bottom view of the design of FIG. 8;
FIG. 13 is a front view of the design of FIG. 8; and,
FIG. 14 is a back view of the design of FIG. 8.
The broken lines illustrating the half moon patch and the
heel stripe in the above described Figures are for illustrative
purposes only and form no part of the claimed design.
